UNITED STATES PATENT OFFICE.

JOSEPH M. ANGELETTI, OF NEW YORK, N. Y.

HAIR CUTTER.

Application filed January 21, 1921. Serial No. 438,904.

To all whom it may concern:

Be it known that I, JOSEPH M. ANGELETTI, a subject of the King of Italy, and a resident of New York, in the county of 5 New York and State of New York, have invented certain new and useful Improvements in a Hair Cutter, of which the following is a full, clear, and exact specification.

10 This invention relates more particularly to a class of cutting devices.

My invention has for its object primarily to provide a device or cutter designed to be employed for cutting with facility the hair especially of persons by one who may be skilled or unskilled in the art as well as enabling persons with little practice to neatly trim their own hair, and which is of a form adapted to allow the hair to be 20 closely trimmed or permit long hair to be cut to various lengths or trimmed in a graduated fashion as occasion requires. The invention contemplates the provision of a clipper composed mainly of a supporting 25 bar below which may be one row of teeth or two spaced rows of oppositely disposed teeth having cutting edges, and these rows of teeth are carried by the supporting bar so as to be adjustable toward and from the 30 underside of the bar. Between the adjustable rows of teeth and the supporting bar may be a slidably movable single row or two spaced rows of slidably movable teeth all with cutting edges in opposition to the 35 cutting edges of the adjustable rows of teeth. The slidable rows of teeth are normally arranged under the supporting bar upon and in movable engagement with the rows of adjustable teeth so that the slidable 40 teeth may be moved in unison across the adjustable teeth for causing the cutting edges of the pairs of teeth of each row to coact in cutting material therebetween. Pivoted at one end of the supporting bar is a pair 45 of spring actuated handles which are operably connected to the slidable rows of teeth whereby the slidable teeth may be yieldingly moved back and forth to cause coaction of the teeth of each pair of rows, in order to 50 accomplish the cutting process.

The invention also contemplates the provision of a combing device for causing long hair to be combed in between the teeth of the clipper, and this device consists essentially of one or two spaced rows of oppo-

sitely protruding spaced prongs, and in spaced proximity to the underside of the rows of prongs is a plate having one or two rows of oppositely projecting prongs, while between this pronged plate and the 60 rows of prongs thereabove may be one or two spaced rows of curved fingers having one of their end parts pivotally held so that the second end parts of the fingers of each row are disposed for being moved simultaneously back and forth crosswise of the prongs. These parts of the combing device may be hinged to the supporting bar for being swung toward and from the underside of the adjustable rows of teeth as 70 well as being adapted to be releasably locked to the supporting bar, and the rows of curved fingers are movable by a manually operable lever so that when it is desired to cut long hair the strands may be combed 75 in between the rows of cutting teeth. Also to the supporting bar may be swiveled a handle for enabling the apparatus to be conveniently manipulated with both hands of a person to facilitate the trimming and 80 cutting process.

A further object of the invention is to provide a hair cutter of a simple and efficient construction which may be made in any appropriate size and shape. 85

With these and other objects in view, the invention will be hereinafter more fully described with reference to the accompanying drawings forming a part of this specification in which similar characters of reference indicate corresponding parts in all the views, and will then be pointed out in the claims at the end of the description. 90

In the drawings, Figure 1 is a top plan of one form of hair cutter embodying my 95 invention.

Fig. 2 is a side elevation of the cutter.

Fig. 3 is an enlarged top plan of the adjustable toothed plate used in the clipper of the cutter.

Fig. 4 is an enlarged top plan of the slid- 100 able plate used in the clipper.

Fig. 5 is an enlarged top plan of one of the pronged plates used in the combing device of the cutter.

Fig. 6 is an enlarged top plan of the rows of movable fingers and a second pronged plate used in the combing device.

Fig. 7 is an enlarged fragmentary view showing an inverted plan of one end of the 110

pair of the operating handles used to operate the clipper.

Fig. 8 is a detail sectional view taken lengthwise through the supporting bar of the cutter.

Fig. 9 is an enlarged fragmentary view showing an end elevation of the operating handles of the clipper.

Fig. 10 is an enlarged plan of the spring used with the pair of handles of the clipper.

Fig. 11 shows an end view of the toothed plates illustrated in Figs. 3 and 4 when assembled, and

Fig. 12 shows an end view, partly in section, of the pronged plates and fingers illustrated in Figs. 5 and 6 when assembled.

The hair cutter has a supporting bar 10 which may be formed with an elongated body part 11 having in its tenderside a lengthwise groove 12 to provide a top plate 13 and two spaced depending walls 14 and 15, Figs. 2 and 8, the free edges of which may be corrugated or notched, as at 16. Through the top plate 13 of the bar part 11 may be a number of spaced openings 17 which lead into the groove between the notched edged walls 14 and 15. Extending from the top plate 13 at one end of the body part 11 is a flat disk 18 having a central opening 19 with a boss, as 20, protruding downward from its underside surrounding the opening 19, and projecting downward from the edge of the disk 18 opposite to the body part of the supporting bar may be a lug 21 having a threaded hole 22. Protruding from the walls 14 and 15 at the second end of the body part 11 of the supporting bar are two spaced ears, as 23 and 24, having in their central parts registered holes 25, while in the free ends of the lugs may be registered notches, as 25a.

Under the supporting bar 10 in spaced relation to the notched edged walls 14 and 15 is a clipping device 26 adapted to cut hair, and this clipper is composed of a plate, as 27, of a length so that one of its ends rests under the end of the lug 21 of the supporting bar, while the other end of the plate extends under the body part 11 of the supporting bar as well as terminating in spaced proximity to the ears 23 and 24 of the side walls of the supporting bar. Projecting in opposite directions from the parts of the edges of the plate 27 which are under the body part 11 of the supporting bar 10 are spaced rows of teeth, as 28 and 29, all with corresponding cutting edges 30, and while this plate has two rows of the cutting teeth forms of the plate may be made having a single row of the cutting teeth. Extending lengthwise of the upper face of the toothed plate 27 may be a groove 31, and in the bottom of the groove are spaced openings 32 two of which are in register with the openings 17 of the body part 11 and the other is

in register with the opening 19 of the disk 18 of the supporting bar 10. Between the toothed plate 27 and the supporting bar 10 is an elongated plate 33 having on one of its ends a flat substantially oval disk like head 34 with spaced openings, as 35a, provided at distances beyond the side edges of the plate 33. Extending in opposite directions from the side edges of the plate 33 are spaced rows of teeth, as 36 and 37, and these teeth have corresponding cutting edges adapted to coact with the teeth of the plate 27 for cutting material therebetween. The plate 33, head 34 and teeth 36 and 37 are proportioned as well as being arranged on the plate 27 so that the rows of teeth 36 and 37 may be slideable upon the rows of teeth 28 and 29 of the plate 27 for being moved back and forth crosswise of the teeth 28 and 29. In the central part of the plate 33 between its teeth 36, 37 and in the head 34 are spaced slots, as 38, two of which are in register with the spaced openings 32 of the plate 27 and the third slot is in register with the opening 19 of the disk 18 of the supporting bar 10. Extending downwardly from the underside of the plate 33 between the slots 38 are two lugs, as 39 and 40, which are movably disposed in the groove 31 of the toothed plate 27 to serve as a guide for causing the plate 33 to move so that the teeth of the plates 27 and 33 will accurately co-operate, and in the top face of the plate 33 between the rows of teeth 36 and 37 may be a groove 41 in which is disposed the notched edges of the walls 14 and 15 of the supporting bar 10. While the plate 33 has two rows of teeth, forms of the plate may be made having a single row if desired. The toothed plates 27 and 33 are removably held to the supporting bar 10, while the plate 27 is adjustable toward and from the bar, in order to hold both of the toothed plates in operative engagement, and to accomplish this threaded bolts, as 42, 43, 44, are provided in the openings 32 of the plate 27 and in the slots 38 of the plate 33. These bolts also pass through the openings 17 and 19 of the supporting bar 10, and on the ends of each of the bolts is a nut 45 adapted to be screwed on its bolts into engagement with the supporting bar 10 to loosen and tighten the toothed plates 27 and 33 to the side walls 14 and 15 of the supporting bar.

These parts of the clipping device 26 are operated by a pair of spring actuated handles, as 46 and 47, both of which may be similarly formed. Each of the handles 46 and 47 has a bar 48 with one of its ends curved downwardly, then inwardly toward each other and somewhat right angularly outward in opposite directions to provide laterally extending fingers, as 49. The free ends of the fingers 49 are bent in the fashion of hooks, as 50, and in the angles of the fin-

gers 49 with the bars 48 are registered holes 51. The bars 48 with the fingers 49 are relatively arranged in overlapping positions under the boss 20 of the disk 18 of the supporting bar 10 and upon the disk 34 of the toothed plate 33 so that the registered holes 51 are in register with the opening 19 of the supporting bar 10. The bolt 44 which is disposed through one of the openings 32 of the toothed plate 27 and through the slot 38 of the disk 34 of the toothed plate 33 also passes through the registered holes 51 of the handles 46, 47 and through a boss, as 52, which extends from one of the handles rotatably into the boss 20 of the supporting bar 10. The bolt 44 also passes, as above explained, through the opening 19 of the supporting bar, and the handles are tightened or loosened as desired to the supporting bar 10 by screwing the nut 45 of this bolt accordingly. The hooks 50 of the fingers 49 are engaged in the openings 35 and 35^a of the disk 34 of the toothed plate 33 for operatively connecting the handles to this toothed plate. On the bars 48 of the handles 46 and 47 may be finger pieces, as 53 and 54, one in the form of a ring and the other in the form of a split or partial ring, as shown, to allow the operator of the apparatus to pass two fingers of one hand therethrough for conveniently operating the clipping device. Each of the finger pieces 53 and 54 has an apertured lug 55, which are movably disposed upon the bars 48 of the handles so that the finger pieces or rings 53 and 54 may be suitably adjusted on the bars 48, and in each of the lugs is a threaded hole with a set screw 56. The set screws 56 are adapted to be rotated into and out of engagement with the bars 48 of the handles for tightening the finger pieces to the bars when suitably positioned. Encircling the boss 20 of the supporting bar 10 is a spring, as 57 Figs. 1, 8, 10, having diverging extending end parts 58 and 59 which are in movable engagement with the bent end parts of the bars 48 of the handles 46 and 47. The handles are disposed so that they protrude rearwardly of one end of the supporting bar 10, and the spring 57 is tensioned for normally serving to yieldingly hold the handles in spaced relation so that when the bars 48 of the handles are swung toward each other against the tension of the spring 57 the fingers 49 of the handles will cause the plate 33 to slidably move toward the second end of the supporting bar for moving the rows of teeth 36 and 37 across the rows of teeth 28 and 29 of the plate 27 to cut hair therebetween.

60 In order to enable long strands of hair to be trimmed by the clipping device 26, I provide a combing device, as 58. This combing device has elongated plate 59 arranged in closely spaced proximity to the underside 65 of the toothed plate 27 of the clipping de-

vice 26. Protruding in opposite directions from the lengthwise edges of the plate 59 may be two spaced rows of prongs, as 60 and 61, and this plate is of a width and length so that the prongs protrude beyond 70 the teeth of the plates 27 and 33 of the clipping device 26. One end of the pronged plate 59 is hinged, at 62, to a small flat plate or tongue, as 63, which is swung upwardly in proximity to the lug 21 of the top plate 75 11, and in the tongue is a threaded hole 64 in register with the threaded hole 22 of the lug 21 of the supporting bar. Through the registered threaded holes 22 and 64 is a screw, as 65, for removably connecting the 80 pronged plate 59 to the supporting bar 10 so that the combing device may be swung toward and from the underside of the clipping device 26. On the second end of the pronged plate 59 is an upwardly extending 85 lug 66 which is disposed against the end of the supporting bar 10 between the spaced ears 23 and 24 of the bar, and protruding from the lug 66 is a pin 67 which is removably inserted in a hole provided in the second end of the supporting bar for detachably fastening the second end of the combing device to the supporting bar. Spaced under the pronged plate 59 is another plate 68 of a similar size and shape to the plate 59, 90 and the ends of the plate 68 may be soldered or otherwise secured to the ends of the plate 59. Projecting in opposite directions from the lengthwise edges of the plate 68 are two spaced rows of prongs, as 69 and 70, and 100 the number of prongs of these rows are preferably less than the number of prongs of the plate 59 so that the prongs of the plate 68 are spaced wider apart than the prongs of the plate 59. In the top face of the 105 pronged plate 68 between the rows of prongs 69 and 70 is a lengthwise groove 71, and slidably movable in this groove from end to end of the pronged plate 68 is a bar 72 having two spaced pins or lugs 73 and 74 projecting upwardly from one end part of its top face. Also projecting upwardly from the pronged plate 68 in spaced proximity to the pins 73 and 74 of bar 72 are two pins 75 and 76, and extending upwardly from 115 the pronged plate in spaced proximity to the pins 75 and 76 are two more pins 77 and 78. The pin 75 is encircled by the loop 79 of a spiral spring 80 formed with projecting ends 81 and 82 so that one end of the spring abuts against the pin 73 of the bar 72 and so that the second end of the spring abuts against the pin 77 of the pronged plate 68. The pin 76 of the plate 68 is encircled by the loop 83 of another 120 spiral spring 84 formed with projecting ends 85 and 86 so that one end abuts against the pin 74 of the slideable bar 72 and so that the second end of the spring 84 abuts against the pin 78 of the plate 68. The springs 80 130

and 84 are tensioned for normally forcing the bar 72 in the groove 71 of the plate 68 so that the bar is normally held yieldingly whereby the second end of the slideable bar 5 extends some distance beyond the end of the pronged plate 68 under the end of the supporting bar 10 opposite to the handles 46 and 47. On top of the pronged plate 68 and on the top of the slideable bar 72 are two 10 rows of oppositely disposed curved fingers, as 87 and 88, adapted to be swung yieldingly crosswise of the prongs 69 and 70 of the plate 68. All of these fingers are alike in formation, and each finger has a tapered 15 or pointed end part 89 and an end part 90 curved in substantially the shape of a quadrant with a curved slot 91 extending throughout its length. The fingers of each row are relatively arranged so that the free 20 ends of the slotted parts of the fingers of one of the rows overlap the free ends of the slotted parts of the fingers of the second row and these overlapping ends of the fingers are pivoted to the yieldingly mov- 25 able bar 72 by pins, as 92, one of which is disposed through the registered slots of the overlapping parts of each pair of the fingers. The fingers 87 and 88 are also arranged so that their pronged ends 89 are movably dis- 30 posed above the prongs 69 and 70 of the plate 68 at positions so that the prong of each finger is approximately midway between each pair of the prongs 69 and 70 of the plate 68, and the central part of 35 each of the fingers is also pivoted to the pronged plate 68 by fixed pins, as 93, which extend upwardly from the plate 68 so that one of the pins 93 is disposed through the second end of the slot 91 of each of the 40 fingers to allow the fingers to be swung on the pivots or pins 93. The end of the bar 72 projecting beyond the pronged plate 68 pivoted, at 44, to the lower end of a lever, as 95, which is movably disposed between 45 the spaced ears 23 and 24 so that the upper end of the lever extends above the supporting bar, and this lever is fulcrumed, intermediate its ends, as at 96, to the ears 23 and 24. When the combing device 58 is 50 operated for allowing long strands of hair to be cut by the clipping device 26 the apparatus is manipulated by passing the prongs of one of the pairs of rows of the prongs of the plates 59 and 68 as well as 55 passing the row of fingers 87 or 88 between the pairs of prongs into the required depth of the hair. The lever 95 is then moved on its fulcrum to move the slideable bar 72 so that the fingers will be swung on their pivots 60 93 for causing the prongs 89 of the fingers to be moved crosswise of the pairs of prongs of the plates 59 and 68 under and above the moving prongs of the fingers inserted in the hair. The strands of hair will then be 65 moved into contact with the teeth of the

plates 27 and 33 thereabove, and by operating the clipping device, as above explained, the hair will be cut.

To permit the apparatus to be carried and manipulated by both hands of the operator, 70 a handle, as 97, is provided on the end of the supporting bar 10 opposite to the handles 46 and 47. The handle 97 has a ring, as 98, for admitting a finger of the operator, and protruding from this ring may be 75 a lug, as 99, which is swiveled to the supporting bar 10 by a suitable form of universal joint, such as being hinged, as at 100, to one end of a finger 101 having its other end pivoted, as at 102, to one end of a bar, 80 as 103, having on its other end spaced ears, as 104 and 105. The ear 104 may be longer than the ear 105, and the end of this ear is hinged, at 106, to the protruding ear 23 of the supporting bar 10. Hinged, at 107, 85 to the free end of the ear 105 of the bar 103 is a plate 108 adapted to be swung upon and from the ear 24 of the supporting bar 10, and in the hinged plate 108 as well as in the ear 24 are registered threaded holes in which 90 is inserted a finger screw, as 109, for releasably locking the bar 103 and the handle 97 to the supporting bar 10. By hinging the ring 98 to the finger 101 the ring may be 95 swung back and forth crosswise of the supporting bar 10, and by pivoting this finger to the hinged bar 103 the ring may be rotatably moved for allowing the apparatus to be moved to various desired positions when in use for trimming or cutting hair. 100

In the foregoing description, I have embodied the preferred form of my invention, but I do not wish to be understood as limiting myself thereto, as I am aware that modifications may be made therein without departing from the principle or sacrificing any of the advantages of this invention, therefore I reserve to myself the right to make such changes as fairly fall within the scope thereof. 105

Having thus described my invention, I claim as new and desire to secure by Letters Patent:—

1. A hair cutter, comprising a supporting bar, a plate having two spaced rows of oppositely disposed cutting teeth, adjustably mounted on the bar, a second plate slidably movable between the adjustable toothed plate and the bar and having two spaced rows of oppositely projecting cutting teeth 115 cooperating with the teeth of the adjustable plate, a pair of yieldingly pivoted handles held to one end of the supporting bar and connected to the slideable toothed plate for being manually operated whereby said slideable plate will be yieldingly moved back and forth upon the adjustable plate to cause cutting coaction of the teeth of both plates, and two spaced rows of oppositely protrud- 120 ing prongs, hinged to the second end of the 125

130

supporting bar for being swung toward and from the underside of the adjustable toothed plate.

2. A hair cutter, comprising a supporting bar, a plate having two spaced rows of oppositely disposed cutting teeth, adjustably mounted on the bar, a second plate slidably movable between the adjustable toothed plate and the bar and having two spaced rows of oppositely projecting cutting teeth cooperating with the teeth of the adjustable plate, a pair of yieldingly pivoted handles held to one end of the supporting bar and connected to the slidable toothed plate for being manually operated whereby said slid-
able plate will be yieldingly moved back and forth upon the adjustable plate to cause cutting coaction of the teeth of both plates, two spaced rows of oppositely protruding prongs, hinged to the second end of the sup-
porting bar for being swung toward and from the underside of the adjustable toothed plate, and means on the rows of prongs, operable for combing hair between the rows of cutting teeth.

25 cutting teeth.

3. A hair cutter, comprising a supporting bar, a plate having two spaced rows of oppositely disposed cutting teeth, adjustably mounted on the bar, a second plate slidably 30 movable between the adjustable toothed plate and the bar and having two spaced rows of oppositely projecting cutting teeth cooperating with the teeth of the adjustable plate, a pair of yieldingly pivoted handles 35 held to one end of the supporting bar and connected to the slidable toothed plate for being manually operated whereby said slid- able plate will be yieldingly moved back and forth upon the adjustable plate to cause cut- 40 ting coaction of the teeth of both plates, two spaced rows of oppositely protruding prongs, hinged to the second end of the sup- porting bar for being swung toward and from the underside of the adjustable 45 toothed plate, a second pair of spaced rows of oppositely extending prongs held in spaced proximity to the underside of the first mentioned pair of prongs, and means between the spaced pairs of prongs, oper- 50 able for combing hair between the rows of cutting teeth.

4. A hair cutter, comprising a supporting bar, a plate having two spaced rows of oppositely disposed cutting teeth, adjustably mounted on the bar, a second plate slidably movable between the adjustable toothed plate and the bar and having two spaced rows of oppositely projecting cutting teeth cooperating with the teeth of the
55 adjustable plate, a pair of yieldingly pivot-ed handles held to one end of the support-ing bar and connected to the slidable toothed plate for being manually operated whereby
60 said slidable plate will be yieldingly moved back and forth upon the adjustable plate to
65

cause cutting coaction of the teeth of both plates, two spaced rows of oppositely protruding prongs, hinged to the second end of the supporting bar for being swung toward and from the underside of the adjustable toothed plate, a second pair of spaced rows of oppositely extending prongs held in spaced proximity to the underside of the first mentioned pair of prongs, a slid-
able bar between the spaced pairs of prongs, and two rows of curved fingers having one of their ends pivoted to the slidable bar so that their second ends are movable between and lengthwise of the spaced pairs of prongs.

5. A hair cutter, comprising a supporting bar, a plate having two spaced rows of oppositely disposed cutting teeth, adjustably mounted on the bar, a second plate slidably movable between the adjustable 85 toothed plate and the bar and having two spaced rows of oppositely projecting cutting teeth cooperating with the teeth of the adjustable plate, a pair of yieldingly pivoted handles held to one end of the supporting bar and connected to the slidable toothed plate for being manually operated whereby said slidable plate will be yieldingly moved back and forth upon the adjustable plate to cause cutting coaction of the teeth of both plates, and a slidable bar between the toothed plates, and two rows of curved fingers having one of their ends pivoted to the slidable bar so that their second ends are movable between and lengthwise of the 90 95 100 toothed plates.

6. A hair cutter, comprising a supporting bar, a plate having two spaced rows of oppositely disposed cutting teeth, adjustably mounted on the bar, a second plate 105 slidably movable between the adjustable toothed plate and the bar and having two spaced rows of oppositely projecting cutting teeth cooperating with the teeth of the adjustable plate, a pair of yieldingly pivoted handles held to one end of the supporting bar and connected to the slidable toothed plate for being manually operated whereby said slidable plate will be yieldingly moved back and forth upon the adjustable plate to cause cutting coaction of the teeth of both plates, a slidable bar between the toothed plates, two rows of curved fingers having one of their ends pivoted to the slidable bar so that their second ends are movable between and crosswise of the spaced pairs of prongs, and a fulcrumed lever pivoted to the slidable bar for being moved to swing the curved fingers back and forth lengthwise of the rows of prongs. 110 115 120 125

7. A hair cutter, comprising a supporting bar, a plate having two spaced rows of oppositely disposed cutting teeth, adjustably mounted on the bar, a second plate slidably movable between the adjustable 130

toothed plate and the bar and having two spaced rows of oppositely projecting cutting teeth cooperating with the teeth of the adjustable plate, a pair of yieldingly pivoted handles held to one end of the supporting bar and connected to the slidable toothed plate for being manually operated whereby said slidable plate will be yieldingly moved back and forth upon the adjustable plate to cause cutting coaction of the teeth of both plates, two spaced rows of oppositely protruding prongs, hinged to the second end of the supporting bar for being swung toward and from the underside of the adjustable toothed plate, a second pair of spaced rows of oppositely extending prongs held in spaced proximity to the underside of the first mentioned pair of prongs, a slidable bar between the spaced pairs of prongs, two rows of curved fingers having one of their ends pivoted to the slidable bar so that their second ends are movable between and crosswise of the spaced pairs of prongs, and a fulcrumed lever pivoted to the slidable bar for being moved to swing the curved fingers back and forth lengthwise of the rows of prongs.

8. A hair cutter, comprising a supporting bar, a plate having two spaced rows of oppositely disposed cutting teeth, adjustably mounted on the bar, a second plate slidably movable between the adjustable toothed plate and the bar and having two spaced rows of oppositely projecting cutting teeth cooperating with the teeth of the adjustable plate, a pair of yieldingly pivoted handles held to one end of the supporting bar and connected to the slidable toothed plate for being manually operated whereby said slidable plate will be yieldingly moved back and forth upon the adjustable plate to cause cutting coaction of the teeth of both plates, two spaced rows of oppositely protruding prongs, hinged to the second end of the supporting bar for being swung toward and from the underside of the adjustable toothed plate, a second pair of spaced rows of oppositely extending prongs held in spaced proximity to the underside of the first mentioned pair of prongs, a slidable bar between the spaced pairs of prongs, two rows of curved fingers having one of their ends pivoted to the slidable bar so that their second ends are movable between and crosswise of the spaced pairs of prongs, a catch releasably fastening both of the pairs of prongs with the movable fingers to the supporting bar, and a fulcrumed lever pivoted to the slidable bar for being moved to swing the curved fingers back and forth lengthwise of the rows of prongs.

9. In a hair cutter, the combination with a supporting bar, and relatively slidable operative cutting teeth, of a slidable bar associated with the cutting teeth, two rows of

curved fingers having one of their ends pivoted to the slidable bar so that their second ends are movable between and crosswise of the spaced pairs of prongs, and a fulcrumed lever pivoted to the slidable bar for being moved to swing the curved fingers back and forth lengthwise of the cutting teeth. 70

10. In a hair cutter, the combination with a supporting bar, and relatively slidable operative cutting teeth, of two spaced rows of oppositely protruding prongs on the underside of the cutting teeth, a slidable bar on the rows of prongs, two rows of curved fingers having one of their ends pivoted to the slidable bar so that their second ends are movable between and crosswise of the spaced pairs of prongs, and a fulcrumed lever pivoted to the slidable bar for being moved to swing the curved fingers back and forth lengthwise of the rows of prongs. 75

11. In a hair cutter, the combination with a supporting bar, and relatively slidable operative cutting teeth, of two spaced rows of oppositely protruding prongs on the underside of the cutting teeth, a second pair of spaced rows of oppositely extending prongs held in spaced proximity to the underside of the first mentioned pair of prongs, a slid- 80 able bar between the spaced pairs of prongs, two rows of curved fingers having one of their ends pivoted to the slidable bar so that their second ends are movable between and crosswise of the spaced pairs of prongs, and a fulcrumed lever pivoted to the slidable bar for being moved to swing the curved fingers back and forth lengthwise of the rows of prongs. 85

12. In a hair cutter, the combination with a supporting bar, and relatively slidable operative cutting teeth, of two spaced rows of oppositely protruding prongs on the underside of the cutting teeth, a second pair of spaced rows of oppositely extending prongs held in spaced proximity to the underside of the first mentioned pair of prongs, a slid- 90 able bar between the spaced pairs of prongs, two rows of curved fingers having one of their ends pivoted to the slidable bar so that their second ends are movable between and crosswise of the spaced pairs of prongs, and a fulcrumed lever pivoted to the slidable bar for being moved to swing the curved fingers back and forth lengthwise of the rows of prongs. 95

13. In a hair cutter, the combination with a supporting bar, and relatively slidable operative cutting teeth, of a row of oppositely protruding prongs, hinged to the second end of the supporting bar for being swung toward and from the underside of the cutting teeth, a second row of oppositely extending prongs held in spaced proximity to the underside of the first mentioned row of prongs, 100

a slidable bar between the rows of prongs, a row of curved fingers having one of their ends pivoted to the slidable bar so that their second ends are movable between and crosswise of the spaced rows of prongs, and a fulcrumed lever pivoted to the slidable bar for being moved to swing the curved fingers back and forth lengthwise of the rows of prongs.

14. In a hair cutter, the combination with a supporting bar, and relatively slidable operative cutting teeth, of a row of oppositely protruding prongs, hinged to the second end of the supporting bar for being swung toward and from the underside of the cutting teeth, a second row of oppositely extending prongs held in spaced proximity to the underside of the first mentioned row

of prongs, a slidable bar between the spaced rows of prongs, a row of curved fingers having one of their ends pivoted to the slidable bar so that their second ends are movable between and crosswise of the spaced rows of prongs, a catch releasably fastening both rows of prongs with the movable fingers to the supporting bar, and a fulcrumed lever pivoted to the slidable bar for being moved to swing the curved fingers back and forth lengthwise of the rows of prongs.

This specification signed and witnessed this 20th day of January A. D. 1921.
